UNITED STATES PATENT OFFICE.

CARL J. LAMB, OF PHILADELPHIA, PENNSYLVANIA, ASSIGNOR TO WESTINGHOUSE ELECTRIC & MANUFACTURING COMPANY, A CORPORATION OF PENNSYLVANIA.

TURBINE.

Application filed June 17, 1925. Serial No. 37,732.

My invention relates to elastic fluid turbines and it has for its object the provision of a method and apparatus for minimizing the time required for starting up a steam 5 turbine after it is shut down.

More specifically, my object is to prevent distortion and to prevent rubbing of the turbine parts by minimizing the temperature differences between the upper and lower 10 parts of the turbine casing and rotor.

In the accompanying drawings forming a part of this specification Fig. 1 is a view, partly in section, of a multi-stage elastic fluid turbine to which my invention is especially applicable; Fig. 2 is a similar view showing a modified form of my invention.

In the operation of power plants, as is well known, there is ordinarily a variation of power demand in a day's operation. During 20 certain hours of the day more power units must be put in service to supply the power demand than during other hours. It follows therefore that in a day's operation one or more units are operated for a part 25 time only and are shut down the other part of the time.

Where elastic fluid turbines are employed as prime movers under the circumstances mentioned, difficulties have been encountered 30 due to the unequal distribution of heat within the turbine casing during idle periods. When the turbine is in operation, the rotor and the casing become heated by the motive fluid; and, as motive fluids having temperatures of 700° F., or more, are frequently admitted to steam turbines, it will be apparent that the rotor and the casing become highly heated. When the turbine is shut down and remains idle for several hours the temperature 35 within the casing becomes greater at the top than at the bottom and the idle rotor and the casing cool off to a greater extent at the bottom than at the top. The lower parts of the rotor and the casing being cooler 40 than the upper parts thereof, such lower parts contract to a greater degree so that the rotor and the casing are caused to bow or bend somewhat due to the differences in temperature between the upper and lower parts.

If now the turbine is again started it will 50 be found to be decidedly out of balance and rubbing of the parts is liable to occur if it is brought up to its designed speed before the heat of the rotor has again become evenly distributed throughout its mass. This difficulty is especially encountered in a turbine 55 having a long rotor of the drum type.

Various expedients have been resorted to in order to overcome the before-mentioned difficulty; that most commonly employed being the provision of a separate motor with suitable gearing to keep the rotor of the idle turbine slowly rotating during its idle periods. This and other expedients known to me are obviously expensive and cumbersome. 60

Another deleterious effect on the turbine which has been found to follow intermittent periods of operation is that considerable condensation occurs within the casing during idle periods. Inasmuch as this condensation 70 takes place in the presence of air, serious corrosion of the turbine passages and blading follows, particularly when formed of iron or steel, entailing overhauling and reblading before it would otherwise be necessary. 75

In accordance with my invention I overcome the before-mentioned difficulties by providing a circulation of a gaseous medium throughout the turbine when idle. This is preferably accomplished by introducing the 80 gaseous medium under pressure into the upper part of the turbine cylinder and allowing it to flow downwardly around the turbine rotor, escaping outwardly through a valve in the lower part of the turbine casing. Where the rotor is relatively long it may be necessary to introduce the gaseous medium at a plurality of points in order to insure an even distribution of heat within 85 the casing.

Practically, the invention has been carried out by connecting a suitable number of conduits with a source of air under pressure and conveying the air under pressure through the conduits to selected points in the turbine 90 casing. I have found that intermittently operated turbines equipped with apparatus in accordance with my invention may be started 95

and brought up to full speed in one-third the time of other turbines not similarly equipped. I have also found that the circulation of air through the turbine prevents condensation 5 therein during idle periods, thus preventing its corrosion.

Referring now to the drawings for a better understanding of my invention I show in Fig. 1 at 10 an elastic fluid turbine having a 10 motive fluid inlet 11 and an exhaust outlet at 12, said exhaust outlet being connected to a condenser at 13. At 14 is shown part of the turbine rotor in section, said rotor being of the drum type and provided with a plurality of rows of moving blades 16—16. The turbine casing is shown at 17 and is provided with a plurality of rows of stationary blades 18—18 all as is well understood 15 in the art to which my invention relates.

Where a turbine such as is illustrated is 20 intermittently operated and no provision is made for maintaining an even distribution of heat within the turbine casing when the turbine is idle, the lower parts of the rotor 25 14 and the casing become cooler than the upper parts thereof causing them to bend and the rotor to become unbalanced. If the turbine is started with the rotor in this condition dangerous vibration is liable to be set 30 up and rubbing between the moving and stationary parts of the turbine may ensue. I accordingly provide a series of conduits 35 19—19 leading to a suitable number of stages of the turbine in the upper part of the turbine casing. The conduits 19—19 are connected to a manifold 21 which is in turn connected to a source of air under pressure 22, such, for example, as the usual air pressure 40 system found in modern power plants.

Each of the conduits 19—19 is provided 45 with a valve 23 adapted to be closed when the turbine is being operated and to be opened for the admission of air under pressure to the casing when the turbine is idle. A valve 24 in the conduit 22 is also provided 50 which shuts off air from the manifold 21 when the apparatus is not in operation. A gauge 26 in the conduit 22 may also be provided for determining the pressure at which 55 the apparatus is operating. By manipulating the valve 24 the operating pressure may be varied. At 27 I show a valve leading from the lower part of the interior of the casing, at the exhaust end thereof, to the atmosphere. When the turbine is shut down, 60 the valve 27 is opened so that there may be a free circulation of air therethrough.

The operation of apparatus in accordance 65 with this modification of the invention will be apparent. When the turbine is shut down, the valve 27 is opened, also the valve 24 and the valves 23. Air from the conduit 22 and manifold 21 now passes through the conduits 19—19 into the casing 17 and flows downwardly around the rotor 14 and out through

the valve 27. Inasmuch as the heat within the turbine casing has a natural tendency to rise, the incoming air under pressure flowing downwardly sets up a flow opposite to the natural flow tendency and causes the turbine rotor to be maintained at an even temperature throughout its mass. In addition to maintaining the turbine rotor at an even temperature the air entering through the conduits 19—19 drives all moisture out of the 70 turbine casing and prevents corrosion, by means of mechanical displacement.

It will be apparent that by disposing the conduits longitudinally of the turbine, I provide for an even distribution of air along the 80 rotor and thereby maintain an even distribution of heat longitudinally of the rotor. Air is admitted over a period sufficient to maintain the temperature differences between the upper and lower portions of the 85 casing and of the rotor at such low values that, after shut down, a minimum time is required for re-starting.

Referring now to Fig. 2 I show a modified form of my invention. Instead of introducing pressure from an outside source, air within the turbine casing is kept in circulation during idle periods of the turbine. In accordance with this modification I provide a blowing apparatus 28 having an inlet conduit 29 connected to the bottom part of the turbine casing and a discharge conduit 31 connected to the upper part of the turbine casing. During idle periods of the turbine 10 the valve 27 is opened, admitting air to the interior of the turbine casing and the blower 28 is put in operation. Air is then sucked from the bottom part of the turbine casing through the blower and discharged 15 into the upper part of the turbine casing 100 from whence it flows downwardly around the turbine rotor to the blower suction 29 thus maintaining a circulation of air downwardly around the rotor.

While I have illustrated my invention as 110 employing air for the circulating medium through the turbine during idle periods, this has been done solely because air is, at the moment, the most available medium to be employed. It will be obvious however, that 115 any other gaseous medium might be employed so long as it is circulated in the manner herein set forth for maintaining an even distribution of heat and preventing condensation within the turbine during idle periods.

From the foregoing it will be apparent 120 that I have invented an improved method of securing an even distribution of heat within an idle turbine which is simple and easy of application, and which also prevents corrosion within the interior of the turbine.

While I have shown my invention in but 125 two forms, it will be obvious to those skilled in the art that it is not so limited, but is susceptible of various other changes and 130

modifications, without departing from the spirit thereof, and I desire, therefore, that only such limitations shall be placed thereupon as are imposed by the prior art or as are specifically set forth in the appended claims.

What I claim is:

1. The combination with a multi-stage turbine having a rotor and a casing, of means for securing an even distribution of heat through the turbine along the rotor when idle, comprising a distributing manifold adapted to be connected to a source of gaseous medium under pressure, conduits leading from the manifold to the various turbine stages in the upper part of the turbine casing, and means for withdrawing the gaseous medium from the lower part of the casing.

2. The combination with a multi-stage turbine having a rotor and a casing, of means for insuring an even distribution of heat through the turbine along the rotor and preventing corrosion of the interior thereof when idle, comprising a plurality of conduits adapted to be connected to a source of gaseous medium under pressure and communicating with the interior of the turbine casing at selected points in a longitudinal row in the upper part thereof, and means for exhausting the gaseous medium from the turbine casing.

3. The method of effecting an even distribution of heat and preventing corrosion within an idle multi-stage turbine, said turbine having a casing, a rotor and a valve in the lower part of the casing adapted to be opened when the turbine is standing idle, comprising opening the valve at the lower part of the casing, and introducing air under pressure into the interior of the casing at a plurality of points longitudinally of the turbine and in the upper part thereof, whereby it circulates downwardly around the rotor and out through the valve.

4. The method of effecting a distribution of heat and preventing corrosion within an idle multi-stage turbine, said turbine having a casing, a rotor and a valve in the lower part of the casing at the exhaust end thereof adapted to be opened when the turbine is standing idle, comprising opening the valve at the exhaust end of the casing, introducing air under pressure into the interior of the casing at various selected stages in the upper part of the turbine whereby it circulates downwardly around the rotor and out through the valve.

5. The combination with a multi-stage turbine having a rotor and a casing, of means for securing an even distribution of heat along the rotor when idle, comprising a plurality of conduits adapted to be connected to a source of gaseous medium under pressure and communicating with the interior of the turbine at a number of points

extending longitudinally of the casing, and means located in the casing opposite said points for discharging gaseous medium from the turbine casing.

6. The combination with a multi-stage turbine having a rotor of the drum type and a casing, of means for securing an even distribution of heat along the rotor when idle, comprising a plurality of conduits adapted to be connected to a source of gaseous medium under pressure and communicating with the interior of the turbine at a number of points in a row extending longitudinally of the casing, and means located in the casing opposite said row for discharging gaseous medium from the turbine casing.

7. The combination with a multi-stage turbine having a rotor and a casing, of means for securing an even distribution of heat along the rotor when idle, comprising a plurality of conduits adapted to be connected to a source of gaseous medium under pressure and communicating with the interior of the casing at various stages throughout the length of the turbine including the high-pressure stage, and means communicating with the interior of the casing oppositely of said conduits for discharging gaseous medium from the turbine casing.

8. The combination with a multi-stage turbine having a rotor and a casing having an exhaust end, of means for insuring an even distribution of heat along the rotor, comprising a plurality of conduits connected to a source of gaseous medium under pressure and communicating with the interior of the turbine at a number of points in a row extending longitudinally of the casing at the top thereof, and means located in the lower part of the casing at the exhaust end for discharging gaseous medium from the turbine casing.

9. The method of minimizing distortion of a turbine rotor and casing in order to reduce the time required for starting after shut down which consists in maintaining minimum temperature differences between upper and lower parts of the turbine casing and rotor after shut down and until the turbine is re-started by passing a gaseous medium through the space between the casing and the rotor, continuing said operation after the moisture has been removed from said space, in order to prevent the accumulation of heat at the upper portions of the casing and rotor.

10. The method of maintaining an even distribution of heat in the stator and the rotor of a turbine when standing idle, which embodies passing a current of fluid through said turbine, uniformly distributing said fluid among the spaces within the turbine, and discharging said fluid from the turbine.

11. The combination with a multi-stage turbine having a rotor and a casing, of

means for insuring an even distribution of heat along the rotor, comprising at least one conduit connected to a source of gaseous medium under pressure and communicating with the interior of the turbine at an intermediate stage thereof and at the top of the casing, and means at the lower part of the

casing for discharging gaseous medium therefrom.

In testimony whereof, I have hereunto ¹⁰ subscribed my name this second day of June 1925.

CARL J. LAMB.
